HUMIDITY CABINET

Joseph A. Lawler, Chicago Heights, Ill., assignor to Blue M Electric Company, Blue Island, Ill., a corporation of Illinois

Filed Apr. 20, 1959, Ser. No. 807,715
17 Claims. (Cl. 165—21)

This application is a continuation-in-part of Serial No. 590,951, filed June 12, 1956, and now abandoned.

The invention relates generally to an improved apparatus for controlling a condition of air in a confined chamber and particularly to a mechanical convection, controlled humidity device.

It is well known in the art that there is a need for a type of equipment that will allow the user to test products under a varying range of temperature and humidity conditions that the manufactured product may be subjected to in actual use. Particularly, it is necessary for many laboratories and manufacturers and the like to have equipment of this nature that will assure them accurate and reliable test results. With this in mind, it may be well to briefly consider certain prior art efforts to provide controlled temperature and humidity conditions. One frequently used method involves the disposition of chemicals or chemical solutions in a confined chamber such as a desiccator jar. Experience has shown that this method is unsatisfactory for many reasons, among them being its high degree of inaccuracy and difficulty of use with the result that only experienced personnel can utilize it with any degree of accuracy. Mechanical devices for controlling temperature and humidity in confined spaces have also been manufactured, but here again experience has shown many disadvantages. In the first instance the designs on the market today are extremely expensive, and have been found to be bulky and difficult to work with. Further, these devices have generally not had the flexibility to afford rapid change in controlled conditions, hence have been unsatisfactory in many use applications. These undesirable features have placed these prior art devices outside the practical scope of most users.

Accordingly, it is a primary object of the invention to provide an improved mechanical convection, controlled temperature and humidity device.

Particularly, it is an object of the invention to provide an automatic, economical and conveniently operable mechanism of the type under consideration offering accurate controlled temperature and humidity conditions, and designed to accommodate rapid and accurate change of controlled conditions. Another feature of the invention is ease of operation.

Other objects and advantages of the disclosed arrangement will appear in the course of the following description and from an examination of the attached drawings, wherein:

FIGURE 1 is a perspective view of an embodiment of the invention,

FIGURE 2 is a top plan view of the structure shown in FIGURE 1,

FIGURE 3 is a sectional view, partially in elevation, taken along line 3—3 of FIGURE 2,

FIGURE 4 is a sectional view, partially in elevation, taken along 4—4 of FIGURE 3,

FIGURE 5 is a schematic of the electrical arrangement employed in the invention, and

FIGURE 6 is a schematic view of a portion of the control circuit employed in the arrangement.

Describing the invention in detail, and directing attention to FIGURE 1, it will be seen that the humidity arrangement may comprise a base cabinet 2, which preferably is a rust-resistant metal cabinet of any desired configuration. The cabinet 2 is provided with an upper

2

horizontal wall 4, upon which rests a transparent jar 6. In the preferred embodiment and for reasons of economy and efficient operation, the jar 6 may be made of transparent, heat-resisting material, and is of cylindrical form. 5 This avoids the manufacture of a chamber having heavily insulated walls and of rust-resistant material, and additionally provides for convenient visual inspection of work pieces during tests and enables photographs thereof to be taken from many positions. The open end of the jar 6 10 faces downwardly and rests upon the upper surface of the wall 4. The jar 6 is demountable which again provides convenient accessibility to the work chamber and any specimens therein.

The cabinet 2 is provided with a control panel 8 on the front thereof having knobs, switches and warning lights which control and visually indicate the operation of the arrangement, as will hereinafter be more particularly described. One side of the cabinet 2 includes an upwardly facing, open-ended housing 10, said housing 10 receiving 20 a jar 12 or the like which provides a reservoir of liquid such as water, the use of which will also hereinafter be more fully described.

The glass jar 6 may enclose a plurality of upstanding supporting members 14, 14 which connect to wall 4, said members 14 supporting a shelf 16 which may hold work pieces during operation of the arrangement. In effect, the jar 6 defines with the wall 4 a workpiece chamber 18 internally thereof. A radially inwardly directed arm 20 may be secured to an upper end of one of the members 14 and may carry centrally of the chamber 18 and adjacent the top of jar 6, a drip plate 22 which will catch any condensed liquid that may collect on the top of the jar and prevent same from falling on the work pieces in the chamber 18. FIGURE 2, a top plan view of the structure 30 shown in FIGURE 1, clearly illustrates the physical relation of the parts of the structure described.

Directing attention to FIGURE 3, it will be seen that the cabinet 2 has provided therein a conditioning chamber 24, said conditioning chamber being located immediately below the wall 4. A central aperture or passage 26 is provided in the wall 4 and establishes communication between the workpiece chamber 18 and the conditioning chamber 24. A pivoted damper plate 27 may be provided to selectively vary the area of the passage 26 40 or even to complete closure, the use of which will be later explained in detail. The chamber 24 is arranged to contain a substantially static liquid pool 28, usually water, at the bottom thereof and having a surface 30 generally coextensive with the area of the conditioning chamber 24. The jar 12, disposed in said housing 10, is positioned with its open mouth facing downwardly and supported in spaced relation to the bottom of the housing whereby the liquid therein is allowed to escape into the housing and is carried via pipe 32, which communicates 50 with chamber 24, so as to maintain a substantially constant level of liquid in the conditioning chamber 24 to replenish any evaporation therefrom which may escape from the system.

An operator motor 34 may be positioned in the bottom 60 of the cabinet 2 in any suitable manner, such as by mounting to a supporting bracket 36. The motor 34 has its rotatable operating shaft 38 extending upwardly through a liquid-tight aperture 40 in the bottom of the conditioning chamber 24. A centrifugal blower 42 is fixedly secured to shaft 38, and is positioned immediately below the aperture 26 in the wall 4. When the motor 34 is operating, as hereinafter described, air will be moved 65 from workpiece chamber 18 through the passage 26 by the blower 42 and then discharged generally outwardly therefrom.

Cooling means may be provided in operative heat ex-

change relationship with the air circulated by the blower 42, and in the preferred embodiment the cooling means comprises a helically wound coil 44 of good conductive material which surrounds the blower 42 radially outwardly therefrom. A first baffle or plate 46 is secured to the underside of the wall 4 and is located outwardly of the coil 44 and in radially spaced surrounding relation thereto.

A second annular baffle or plate 48 is provided in the conditioning chamber 24 and adjacent the outer edge thereof, said baffle 48 extending from the wall 4 downwardly to substantially the bottom of the chamber, and in such position that it forms an inverted cone surrounding the previous described structure. It will be noted that the baffle 48 presents an inner surface that is directed upwardly toward a plurality of peripherally disposed apertures or passages 50, 50 which are annularly arranged in the wall 4, and preferably about the periphery of chamber 18. As will readily be observed, any moisture condensing in the workpiece chamber 18 will drain back to the liquid pool 28 through the passages 50. A plurality of mounting clips 52, 52 may be secured to the inner surface of the baffle 48 and provide a convenient means for mounting electrical heating elements 54 which are annularly arranged around the conditioning chamber 24 and immediately below the passages 50. The heating elements 54 constitute the dry bulb heater illustrated in the schematic of FIGURE 5, later to be described. Additionally, a heating element 56 may be disposed in the liquid 28, said heating element 56 constituting the wet bulb heater illustrated in FIGURE 5.

An additional physical feature of the arrangement is a passage or tube 58 which is provided in the cabinet 2 and extends upwardly through the wall 4 should the user desire to connect the test specimens to an external recording device (not shown). An electrical conduit 60 is similarly provided in the cabinet 2 and extends into the workpiece chamber 18 and offers a plurality of electrical connections which communicate with a connection bar 62 externally of the cabinet to provide convenient electrical connection to any workpiece in the chamber 18 should it be desired to operate the specimens during test.

Directing attention to FIGURES 5 and 6, wherein are schematically illustrated the controlling heating and cooling circuits employed in the invention, it will be seen that a main switch 68 is provided, said main switch connecting the electrical circuit, indicated generally at 70, to a conventional power source which may be a standard 120-volt A.C. line. A warning light L-1 is provided across the switch 68 to visually indicate that the arrangement is turned on. Closure of switch 68 immediately energizes the motor 34 which, of course, induces rotation of the blower 42, and circulation of air from the workpiece chamber 18 through the passage 26, through conditioning chamber 24 and upwardly through apertures 50. Another important point in connection with the peripheral location of apertures 50 is that during air circulation, the air passing through apertures 50 will flow upwardly to the top of the chamber 18 before recirculating through the passage 26. This assures complete air circulation through the chamber 18 and results in constant controlled conditions throughout its entire volume.

A dry bulb controlling circuit 72 is provided in the circuit 70, said dry bulb controlling circuit being arranged to operate the dry bulb heaters 54. The dry bulb control 74 comprises a temperature-sensitive element 76 positioned in the workpiece chamber 18, and preferably adjacent the apertures 50. The element 76 senses the temperature in the chamber 18 and control 74 thermostatically responds thereto in a conventional manner to control the application of power to circuit 72, and hence is not structurally described in detail. A power selector switch 78 is also provided in the circuit 72, said switch 78 being a conventional type switch to selectively provide energizing power in three stages to the heating ele-

ments 54—that is, upon proper setting thereof the elements 54 may be connected individually, in series or in parallel to provide varying levels of available heat application, the purpose of which will hereinafter be described. A pilot light L-2 is arranged in parallel with the dry bulb heaters 54 to visually notify the operator when the dry bulb heaters are energized.

A web bulb control circuit 80 is also provided in the circuit 70, said wet bulb circuit controlling the relay 82 which in turn controls the position of a two-position switch 84. The wet bulb control 86 comprises a temperature-sensitive element 88 which is located in the conditioning compartment 24 and preferably in abutting relationship with a portion of the cooling coil 44, as is shown in FIGURES 3 and 4. One fixed contact 90 of the switch 84 is in series relation with the wet bulb heat element 56. Again, a pilot light L-3 is in parallel with the wet bulb heater 56 to visually advise the operator when the wet bulb heater is energized. The other fixed contact 94 of the two-position switch 84 is in series with a solenoid valve 96 which, in turn, controls the application of cooling medium to the cooling coil 44. Again, a pilot light L-4 is arranged in parallel with the solenoid 96 to visually advise the operator when the solenoid is energized, and therefore when cooling medium is flowing.

FIGURE 6 illustrates the piping arrangement to the cooling coil 44, and it will be seen that a line 100 may be connected to a cooling source (not shown). The solenoid valve 96 is in operative series relation in the line 100, said line 100 also having a manually openable and closable valve 102 therein. Another line 104 establishes communication with the cooling coil 44 and a further line 106 communicates with the other end of the coil 44 to carry the cooling medium to exhaust. A by-pass line 108 communicates with the line 100 between the source and the solenoid valve 96 and establishes communication with the line 104 through a manually operated by-pass valve 110. The reason for this by-pass arrangement will be hereinafter explained in detail.

Before considering the operation of the arrangement, those skilled in the art will understand that the range of temperatures and humidities available in a cabinet of this nature is functionally responsive to a minimum temperature available by virtue of the cooling medium used in the coil 44. I have discovered that most tests run by commercial users of equipment of this nature fall into a relatively high humidity range and dry bulb temperature above ambient, and therefore tap water can normally be used as a coolant. However, if an increased range of both temperature and humidity level is desired, they can be made available by merely substituting for the tap water coolant a refrigerant capable of providing lower cooling temperatures.

Directing attention to FIGURE 5, it will be remembered that the power selector switch 78 can be set at low, medium or high range, depending on the particular temperature to be maintained, and thus the general range of average heat input required, in a particular test run. It will also be understood that the dry and wet bulb controls may be provided with dials (not shown) available on the control panel 8, said dials being manually adjustable to a desired temperature calibrated in degrees Fahrenheit or centigrade, whereby a given temperature selection may be easily and quickly located. Of course, the dry bulb control is responsive to temperature of the air exiting into the workpiece chamber, and the wet bulb control is responsive to the temperature in the conditioning chamber and to a small extent, for purposes of minimizing response time, to temperature of the coil 44 which it physically abuts and touches at one point as shown in the drawing. Independent thermometers may be used in the respective chambers to check the accuracy of the calibrated dials and make corrections if necessary.

Considering a typical operation of the arrangement, it will be understood that by reference to a conventional

psychometric chart a determined dry bulb temperature and relative humidity will then afford the user the desired wet bulb temperature to produce the given conditions. The dry bulb and the wet bulb temperature are then properly set, and the arrangement may be turned on by closing switch 68. Closure of switch 68 immediately energizes the motor 34 which sets up a circulation of air by drawing from the workpiece chamber 18 through the central aperture 26 and urging the air outwardly over the cooling coil 44 and, with the aid of baffle 46, over and across the surface 30 of the liquid 28 from whence it is directed upwardly by baffle 48 over the elements 54 and up through the peripheral apertures 50 and into the workpiece chamber 18. Circulation once started is constant and continues during the entire run. The dry bulb control 74 senses the temperatures in the air exiting into the workpiece chamber 18 and energizes the heating element 54, the level of which is determined by the power selector switch 78. The elements 54 continue to heat the passing air until such time as the temperature reaches the desired level in the chamber 18, whereupon they will deenergize in response to action of the control 74. Intermittent action of the control 74 in response to sensed temperature variation of the air exiting into the chamber 18 will intermittently energize the elements 54 and will accurately maintain the dry bulb temperature in the chamber 18.

The circuit through the wet bulb heater 56 responds to the action of the wet bulb control 86 which selectively energizes the relay 82. The switch 84 normally connects contact 94 which establishes a circuit through the solenoid valve 96 which, in turn, accommodates flow of coolant through the coil 44. As the temperature of the air coming into the conditioning chamber 24 is lowered to or slightly below a dew point temperature corresponding to the total volume of water vapor in the air at the selected relative humidity, the wet bulb control 86 energizes the relay 82, bringing the switch 84 to the contact 90 which establishes a circuit through the wet bulb heater 56 energizing same. This, of course, heats the liquid 28 causing an increased rate of evaporation thereof and more rapidly bringing the air in chamber 24 to a saturated condition. This action tends to raise the temperature of the air in chamber 24, and this change is sensed by the wet bulb control 86 which deenergizes the relay 82 and returns the switch 84 to contact 94, which again provides for circulation of coolant through the coil 44 by energizing the solenoid valve 96. Thus, the temperature in chamber 24 is accurately maintained at the approximate desired level. It will be understood that especially in the more frequently used high humidity test conditions, the wet bulb control selectively and alternately energizes the solenoid valve and the wet bulb heater to selectively and alternately provide for heating and cooling of the air and selective heating of the liquid in the conditioning chamber 24, as well as tending to control the rate of evaporation in said conditioning chamber 24. The abutting juxtaposition of the wet bulb sensing element 88 with the coil 44 provides increased sensitivity and more rapid response relative to controlling temperature and humidity condition in the conditioning chamber 24, and therefore improves the efficiency of the entire arrangement. I have found that this feature tends to produce a somewhat greater and more rapid change in the sensing element than in the acted-on medium itself, which results in a finer tolerance control. In effect, medium change is anticipated or rushed in the sense that the conditions may be controlled with a smaller cycling range than could be obtained if only air conditions were being sensed. The value of this operative feature will be appreciated by those who have experienced the difficulty of running high humidity tests without having undesired condensation on test specimens. The accurate and close tolerance control avoids temporary temperature creep during the operating cycle which may otherwise result in periodic condensation on work specimens.

Considering FIGURE 6, it was earlier noted that a manual by-pass valve 110 was provided to afford circulation of cooling medium through the coil 44 to by-pass the control of the solenoid valve 96. This arrangement is desirable when the determined operating conditions in the workpiece chamber 18 involve a relatively high humidity at a comparatively low dry bulb temperature. Operating under these conditions, the solenoid valve 96 is rarely if ever energized, and as a result no coolant will flow through coil 44. On the other hand, the wet bulb control will tend to constantly energize the wet bulb heater with the result that there is a tendency to cause a slight climbing or raising in the temperature of the circulated air, and to prevent this and remove the excess heat produced by the wet bulb heater, it is desirable to open valve 110 and allow a flow of a small quantity of coolant through the coil 44. This effectively removes the excess heat produced and creates a balance of heat input and cooling effect, which result in the accurate maintenance of the desired dry bulb temperature in the workpiece chamber 18 under these extreme conditions.

The pivoted damper plate 27 is available to vary the area of passage 26 and thereby control the rate of air flow through the entire unit. When closed entirely, the air flow is reduced to approximately zero cubic feet per minute and the entire unit becomes, in essence, a gravity incubator accommodating high humidity resulting in desired condensation on work pieces. As the volume of air flow is varied, the rate of evaporation of moisture condensed on test work pieces also varies, as even with high humidity air, the rate of evaporation varies with the rapidity and volume with which the surrounding air moves. This feature is of advantage in conducting tests relating to the rate of evaporation of condensed moisture on work pieces and operation thereunder.

Thus, it will be seen that I have provided a novel device of the type here under consideration that is economical to produce, highly accurate and versatile in operation, and offers advantages and results heretofore not found in the art. The arrangement particularly is adaptable to small, compact, inexpensive units which satisfy the needs of the majority of users of this type of equipment. The device as shown is by way of illustration and not limitation, and may be subject to various modifications without departing from the spirit thereof and the scope of the appended claims.

I claim:

1. A temperature and humidity conditioning device comprising a chamber, an air inlet and air outlet in horizontally spaced portions of the chamber, a substantially stationary pool of liquid in the bottom of the chamber, an enclosing top on the chamber in the region between the air inlet and outlet, variable heat-removal cooling means exterior to the liquid in the air flow path adjacent to the air inlet, the pool of liquid being at least partially in the region of the chamber between the cooling means and the outlet, means to evaporate the liquid into the region between the liquid and the enclosing top, heating means adjacent to the air outlet, a temperature-sensing element in the portion of the chamber between the cooling means and the air outlet responsive primarily to the temperature of the air in said portion, means responsive to said temperature-sensing element to increase the heat removal of the cooling means when the temperature sensed exceeds a preset value and to reduce the heat removal of the cooling means when the temperature sensed falls below a preset value, means for passing air from the inlet to the outlet through the chamber, and means adjacent to the air outlet to control the heating means to maintain the exit temperature constant at a preset value.

2. A temperature and humidity conditioning device comprising a chamber, an air inlet and air outlet in horizontally spaced portions of the chamber, a substantially stationary pool of liquid in the bottom of the chamber, an enclosing top on the chamber in the region between

the air inlet and outlet, variable heat-removal cooling means exterior to the liquid in the air flow path adjacent to the air inlet, the pool of liquid being at least partially in the region of the chamber between the cooling means and the outlet, heating means adjacent to the air outlet, second heating means in the liquid to evaporate the liquid into the region between its surface and the enclosing top, a temperature-sensing element in the portion of the chamber between the cooling means and the air outlet above the surface of the liquid responsive primarily to the temperature of the air in said portion, means responsive to said temperature-sensing means to increase the heat removal of the cooling means and decrease the heat input of the second heating means when the temperature sensed exceeds a preset value and to decrease the heat removal of the cooling means and increase the heat input of the second heating means when the temperature sensed falls below a preset value, means for passing air from the inlet to the outlet through the chamber, and means adjacent to the air outlet to control the heating means to maintain the exit temperature constant at a preset value.

3. The device of claim 2 wherein the means to increase and decrease the heat removal and heat input comprises a double-throw switch connected to selectively energize the cooling means and the second heating means.

4. A temperature and humidity conditioning device comprising a chamber, an air inlet and air outlet in horizontally spaced portions of the chamber, a substantially stationary pool of liquid in the bottom of the chamber, an enclosing top on the chamber in the region between the air inlet and outlet, selectively operable cooling means exterior to the liquid in the air flow path adjacent to the air inlet, the pool of liquid being at least partially in the region of the chamber between the cooling means and the outlet, means for evaporating the liquid, heating means adjacent to the air outlet, a temperature-sensing element in the portion of the chamber between the cooling means and the air outlet responsive primarily to the air temperature in said portion, means responsive to said temperature-sensing element to activate the cooling means when the temperature sensed exceeds a preset value and to deactivate the cooling means when the temperature sensed falls below a preset value, means for passing air from the inlet to the outlet through the chamber, and means adjacent to the air outlet to control the heating means to maintain the exit temperature constant at a preset value.

5. A humidity cabinet comprising a conditioning chamber, a workpiece chamber atop the conditioning chamber, a central air passage and a plurality of symmetrically distributed peripheral air passages connecting the chambers, a body of liquid in the bottom of the conditioning chamber, means for circulating air into the conditioning chamber through the central passage, radially over the surface of the liquid, and out through the peripheral passages, selectively operable cooling means exterior to the liquid in the conditioning chamber closely surrounding the central passage, heating means adjacent to the peripheral apertures, a temperature-sensing element in the portion of the conditioning chamber outwardly adjacent to the cooling means responsive primarily to the temperature of the air in said portion, means responsive to said temperature-sensing element to activate the cooling means when the temperature sensed exceeds a preset value and to deactivate the cooling means when the temperature sensed falls below a preset value, means to evaporate the liquid, and means adjacent to the peripheral passages to control the heating means to maintain the exit temperature constant at a preset value.

6. A temperature and humidity conditioning device comprising a conditioning chamber, a central air passage and a plurality of symmetrically distributed peripheral air passages in the top of the chamber, a body of liquid in the bottom of the chamber, means for circulating air into the conditioning chamber through the central pas-

5 sage, radially over the surface of the liquid, and out through the peripheral passages, selectively operable cooling means exterior to the liquid in the conditioning chamber closely surrounding the central passage, heating means adjacent to the peripheral apertures, a temperature-sensing element in the portion of the conditioning chamber outwardly adjacent to the cooling means responsive primarily to the temperature of the air in that portion, means responsive to said temperature-sensing element to activate the cooling means when the temperature sensed exceeds a preset value and to deactivate the cooling means when the temperature sensed falls below a preset value, means to evaporate the liquid, and means adjacent to the peripheral passages to control the heating means to maintain the exit temperature constant at a preset value.

7. A temperature and humidity conditioning device comprising a chamber, a central air passage and a plurality of symmetrically distributed peripheral air passages in the top of the chamber, a body of liquid in the bottom of the chamber, a blower adjacent to the central passage disposed to draw air therethrough into the chamber and distribute it radially over the surface of the liquid and out through the peripheral passages, a cooling coil surrounding the blower and having a valve controlling the flow of cooling fluid therethrough, first heating means adjacent to the peripheral apertures, second heating means in the liquid, a temperature-sensing element in the portion of the chamber outwardly adjacent to the cooling coil primarily responsive to the temperature of the air in said portion, means responsive to said temperature-sensing element to deactivate the second heating means and open the valve when the temperature sensed exceeds a preset value and to activate the second heating means and close the valve when the temperature sensed falls below a preset value, and means adjacent to the peripheral passages to control the first heating means to maintain the exit temperature constant at a preset value.

8. A humidity cabinet comprising a conditioning chamber, a workpiece chamber atop the conditioning chamber, a central air passage and a plurality of symmetrically distributed peripheral air passages connecting the chambers, a body of liquid in the bottom of the conditioning chamber, a blower adjacent to the central passage disposed to draw air therethrough into the conditioning chamber and distribute it radially over the surface of the liquid and out through the peripheral passages, a cooling coil surrounding the blower and having a valve controlling the flow of cooling fluid therethrough, first heating means adjacent to the peripheral apertures, second heating means in the liquid, a temperature-sensing element in the portion of the conditioning chamber outwardly adjacent to the cooling coil responsive primarily to the temperature of the air in that portion, means responsive to said temperature-sensing element to deactivate the second heating means and open the valve when the temperature sensed exceeds a preset value and to activate the second heating means and close the valve when the temperature sensed falls below a preset value, and means adjacent to the peripheral passages to control the first heating means to maintain the exit temperature constant at a preset value.

9. The conditioning device of claim 8 wherein the temperature-sensing element includes temperature-sensing means partially responsive to the temperature of the coil.

10. A temperature and humidity conditioning device comprising a chamber, an air inlet and air outlet in horizontally spaced portions of the chamber, means for impelling air from the inlet to the outlet, cooling means in the air flow path adjacent to the air inlet portion, adjustably variable temperature control means primarily responsive to air temperature in the region between the cooling means and the air outlet portion to hold said last temperature constant, means including a substantially stationary pool of water on the bottom of the chamber in

said region for saturating the air in said region with moisture, and adjustably variable controlled heating means to heat the outlet air to fixed temperatures, whereby the inlet air is cooled, saturated with vapor at the selected constant temperature fixed by the control means, heated to a selected constant temperature fixed by the controlled heating means, and emitted at the temperature and humidity thus fixed, substantially independently of the conditions of the inlet air.

11. A temperature and humidity cabinet comprising a work space, a conditioning chamber below the work space, means for circulating air from the work space into an inlet portion of the conditioning chamber, through the conditioning chamber, and out of an outlet portion of the conditioning chamber horizontally spaced from the inlet portion and including openings connecting the work space and chamber, means in the inlet portion of the conditioning chamber to cool the air, manually variable means in the region between the inlet portion and outlet portion responsive to air temperature in this region to maintain such temperature at preselected values and to saturate the air at such constant temperature, the saturating means including a body of liquid on the bottom of the chamber, so that moisture condensed in the work space drains back to the body of liquid through the openings, and manually variable means to heat the air to preselected constant temperature in the outlet portion.

12. A temperature and humidity cabinet comprising a conditioning chamber having a substantially horizontal top, a central aperture in the top of the conditioning chamber, apertures in the top of the conditioning chamber dispersed in a circle about said central aperture, a circular enclosure defining a work space atop the conditioning chamber surrounding the circularly dispersed apertures, the apertures being adjacent to the periphery of the work space and the central and peripheral apertures defining the sole air passages between the conditioning chamber and the work space, radially extending circular conditioning means in the chamber including means to control the temperature and humidity of air passing radially through the chamber, and a blower on the axis of the chamber adapted to circulate air radially through the conditioning

chamber, whereby differences in air conditions in the work space are minimized.

13. The cabinet of claim 12 wherein the enclosure comprises a unitary cup-shaped inverted member, whereby the simple enclosure thus formed may be completely removed to give full access to the work space from any direction.

14. A temperature and humidity cabinet comprising the conditioning device of claim 10 having thereabove an enclosure defining a work space, the air inlet and air outlet being in the top of the chamber and defining the sole air paths between the chamber and the work space.

15. The temperature and humidity cabinet of claim 14 wherein one of said air paths is central of the enclosure and the other is substantially uniformly distributed about the bottom of the work space adjacent to the periphery thereof.

16. The temperature and humidity cabinet of claim 15 wherein the enclosure is circular.

17. The temperature and humidity cabinet of claim 16 wherein the enclosure is a unitary inverted cup-shaped member.
